(57) **CLAIM**

The ornamental design for a lighter, as shown and described.

DESCRIPTION

FIG. 1 is a perspective view of a lighter embodying the new design;

FIG. 2 is an elevation view of one side of the lighter shown in FIG. 1;

FIG. 3 is an elevation view of the other side of the lighter shown in FIG. 2;

FIG. 4 is a rear elevation view of the lighter shown in FIG. 1;

FIG. 5 is a front elevation view of the lighter shown in FIG. 1;

FIG. 6 is a top plan view of the lighter shown in FIG. 1; and,
FIG. 7 is a bottom view of the lighter shown in FIG. 1.

The broken lines in the drawings do not form part of the claimed design.
